STARTING BOX

Thomas A. Keen, San Mateo, Calif., assignor to
Hannah M. Smith, River Forest, Ill.

Application October 7, 1935, Serial No. 43,815

13 Claims. (Cl. 119—15.5)

The invention has particularly to do with a portable, fast opening starting box in which several racing dogs are placed before the start of a race and from which all are released simultaneously to start such race. The box may be placed in a position on a track just before a race and then removed immediately after the start or after the last start to be made.

The objects of the invention include, among others, the provision of the following:

- A new and improved starting box;
- A new starting box of improved form;
- An improved portable starting box;
- Quick opening means for a starting box;
- Improved doors for a starting box;
- An improved means for opening starting box doors.

These objects and such other objects as may hereinafter appear are obtained by the novel arrangement and combination of elements herein-after described and claimed. One form of a starting box embodying the invention is illustrated in the accompanying two sheets of drawings, hereby made a part of this application, and in which:

Figure 1 is a view of the starting box in perspective;

Figure 2 is an enlarged front view of the right hand end of the starting box;

Figure 3 is an enlarged view from above of the door opening apparatus; and

Figure 4 is an enlarged rear view of a part of the starting box.

Like reference characters are used to designate similar parts in the drawings and in the following description.

The present invention is of a starting box having a plurality of closed stalls, each stall having a door at the rear for ingress and doors at the front for egress, there being means to open the front doors of all stalls simultaneously. The front doors are shaped and mounted to provide for quick opening and to allow ready egress of the dogs upon the opening of such doors.

The foundation of the starting box is a frame, which may be wood or other material but which, in the form shown, is of metal angle bars. The frame at each end of the box consists of a rear upright 10, a bottom member 11, a top member 12 and a rearwardly slanted front upright 13. The frame may be braced by triangular pieces 14 at the corners. Longitudinal beams 15 and 16 join the top and bottom back corners of the two end frames. The top front corners of the frames are held by a heavy beam which serves

also as a mounting for instrumentalities later to be described. No frame member is necessary between the lower front corners of the end frames as the heavy beam 17 at the top front corners and the internal construction of the starting box provide adequate support. At intervals along the longitudinal members at the rear and the top front beam and at right angles to the long axis of the starting box are interior frame members which serve to position partitions which divide the starting box into a plurality of stalls with spaces between the stalls. The interior frame members are not shown but they are similar to end frames 10, 11, 12 and 13, to which they correspond.

Top 18, end 19 and bottom 26 are closed by plates which, in the form shown, are of a light metal. Plates (not shown) of the same material are attached at each side of the interior frame members to form dividing partitions. The plates forming each partition are spaced apart by the interior frames so that closed spaces are left between stalls. At the front of the box such spaces are closed by plates 20. Similar plates 21 close the spaces at the rear of the box.

At each side of the rear of each stall a track 22 is provided to receive one side of a vertically sliding door 23. Each door is provided with a handle 24 for ready lifting to permit entry of a dog into the stall.

At each side of the front opening of each stall is a square bar. The bar 25 at the right hand side of each opening is long. The bar 25a at the left hand side of each opening is short. Each bar has a cylindrical lower end fitting rotatively in a socket set into the bottom plate 26 of the box. The top end of each bar 25 and 25a is likewise cylindrical, as indicated at 28 in Figure 3, and is journaled in a bearing member 27 mounted on the longitudinal beam 17 at the top of the front of the box. The bearing member 27 for the long bar 25 at the right side of each stall is located near the top of the longitudinal beam 17. The bearing member 27 to receive the short bar 25a at the other side of each stall is mounted near the lower edge of the longitudinal beam.

Attached to each long bar 25 is a door 29 serving to close the right side of the opening of one stall. A complementary door 29a is mounted on the short bar 25a at the other side of the stall. The two doors 29 and 29a meet at the center of the stall to form a complete closure.

The bottom corner and inner edge of each door are bent outwardly of the stall on a line 30, ex-

55

tending diagonally from the top inner corner to the bottom outer corner of each door. The left hand door 29a of each stall has a window 31 set in the outwardly bent part near the bottom of the door.

6 The bearings 27 in which the top ends of the bars are journaled have their bearing portions divided into two parts 27a and 27b. The bars 25a and 25 pass through both parts. Between the two 10 parts and pinned or otherwise securely fastened to each bar is an arm 32. Where so desired the square portion of the bar may be continued through the lower portion 27a of the bearing 27 and up to the top part. The aperture in the 15 arm 32 then is made square to fit the bar, thus preventing relative rotation.

At the outer end of each arm 32 is a pin 33 rotatively set in a suitable aperture in the arm 32.

20 The top of each pin is provided with a socket 32 to receive a door operating rod 34a or 34b. The rod 34a or 34b may be fastened into the socket by means of a pin or set screw or in any other suitable way. One rod 34a runs through all of the sockets in pins 33 which are on the arms 32 25 attached to the long bars 25 in the upper bearings. The second rod 34b passes through the corresponding sockets in the pins 33 on the arms 32 attached to the short bars 25a in the lower bearings. The respective arms 32 are set on the 30 rods 25 and 25a at such an angle that when the upper rod 34a is moved to the right and the lower rod 34b to the left the arms 32 will turn the bars 25 and 25a to open the doors 29 and 29a outwardly.

35 A lever 35 is provided to give simultaneous movement of the two rods 34a and 34b and thus produce simultaneous opening of all the doors. The lever 35 is pivoted at 36 to the top beam. A link 37 has one end pivoted to the lever at a 40 point above the pivot 36. The other end of the link is pivotally attached to a collar 38 which is secured on the upper rod 34a by a pin or set screw or other means. A second link 39 has one end pivoted to the lever 35 a distance below the pivot 36 equal to the distance of the attachment of the link 37 above the pivot 36. Link 39 runs to a collar 40 which is secured to the lower rod 34b.

45 A guide 41 is attached to a bracket 42 mounted in the front beam 17 and serves to steady the lever 35 and determine its extreme position in either direction.

50 A handle 43 for carrying the starting box is pivoted to brackets 44 at each end of the box.

55 An extension 45 of the upper front beam is provided to fit in a post or other guide (not shown) to determine definitely the proper position of the box.

The operation of the starting box is as follows:

60 The front doors 29 and 29a of the box are shut by throwing the lever 35 toward the box. A dog is let into each stall through the rear door 23 and the rear door lowered into position to close the stall. The stalls are so narrow that the dogs can 65 not turn around in them but must face the front doors. To start the race the lever 35 is pulled quickly away from the box. All the front doors are thereby opened simultaneously. The outwardly flared faces of the doors provide a rapid 70 opening at the bottoms. Since each stall is only about twelve inches wide each door has to swing out only approximately six inches. This movement allows a very quick opening and a resulting quick start. The guide 41 stops the lever at 75 such position that each door stands open ap-

proximately in front of the bar 25 or 25a to which it is attached. To close the doors for the next race the lever 35 is again moved toward the box.

It should be noted that by arranging the hinged doors with the inner lower portions thereof bodily outwardly diverted it is possible to so position the windows that each animal will have a clear view of the track ahead without being able to see the animals in the adjacent stalls.

What is claimed as new and is desired to be secured by Letters Patent of the United States is:

1. In a starting box for dog racing, a closure for starting stalls, comprising paired doors, each door being hinged at the outer edge, said doors meeting at their inner edges, and each door having a portion diverted outwardly of said starting box on a line extending substantially from the top inner corner of each door to the bottom outer corner thereof.

2. The closure described in claim 1, and in which one door of each pair of doors is opaque and the other door of each pair has a transparent section, the opaque and transparent doors occupying the same relative position in each pair whereby animals in adjacent stalls cannot see each other.

3. In a starting box having a plurality of stalls, pivoted bars at the right and the left sides of the exit from each stall, a pair of doors for each stall, one door being secured to each of said bars for pivoting therewith, two door opening rods, an arm secured to each of said bars at the right side of each of said stalls and pivoted to one of said rods, an arm secured to each of said bars at the left side of each of said stalls and pivoted to the other of said rods, and lever means for simultaneously moving one rod in one direction and the other rod in the other direction to open said doors.

4. In a starting box for dog racing, a closure for starting stalls, comprising paired doors, each door being hinged at the outer edge, said doors meeting at their inner edges, and each door having a portion adapted when closed to be in the same plane as the corresponding portion of the other door, and a portion diverted outwardly of said starting box on a line extending substantially from the top inner corner of each door to the bottom outer corner thereof, the edges of said diverted portions meeting.

5. In a starting box having a plurality of stalls, pivoted bars at the right and the left sides of the exit from each stall, a pair of doors for each stall, one door being secured to each of said bars for pivoting therewith, two door opening rods, an arm secured to each of said bars at the right side of each of said stalls and pivoted to one of said rods, an arm secured to each of said bars at the left side of each of said stalls and pivoted to the other of said rods, lever means for simultaneously moving one rod in one direction and the other rod in the other direction to open said doors, said lever means being pivotally mounted at a point between its extremities and having one of said rods operably attached to it on one side of the pivot and the other of said rods operably attached to it on the opposite side of said pivot, and a handle on said lever.

6. In a starting cage having an opening, a pair of doors, said doors being hingedly mounted to opposite sides of said opening, said doors meeting along respective edges thereof to form a closure for said opening, a portion of said doors lying in the plane of said opening and the lower portions of said doors adjacent the meeting edges.

being angularly disposed forwardly away from the plane of the opening.

7. In a starting cage having an opening, a pair of doors, said doors being hingedly mounted to opposite sides of said opening, said doors meeting along respective edges thereof to form a closure for said opening, a portion of said doors lying in the plane of said opening and the lower inner portions of said doors being disposed forwardly away from the plane of the opening.

8. A starting cage having an opening therein, and a pair of doors hingedly mounted with respect to the sides of the opening and adapted to meet whereby to form a complete closure for the opening, the central portion of said doors being disposed forwardly away from the plane of the opening.

9. A starting cage having an opening therein, and a pair of doors hingedly mounted at the opening and adapted to meet whereby to form a complete closure for the opening, a portion of the area of said doors being arranged substantially in the plane of said opening and a lower portion of said doors being displaced forwardly away from the plane of the opening.

10. A starting cage having an opening therein, and a pair of doors hingedly mounted at the opening and adapted to meet whereby to form a complete closure for the opening, a portion of the area of said doors being arranged substantially in the plane of said opening and a lower portion of said doors at and near the line of meeting therebetween being displaced forwardly away from the plane of the opening.

11. A starting cage having an opening therein, and door forming means of sufficient area to form a substantially full closure across said opening, said door forming means having hinge means along at least one edge providing an opposite swingable edge, a part of the area of said door forming means being arranged in the plane of the opening, a further portion of said door extending to said swingable edge, said portion being bodily displaced forwardly away from the plane of the opening when the door is in closed position.

12. A starting cage having a plurality of openings therein, paired doors hingedly mounted with respect to the openings, said doors in closed position converging to a point forwardly of the said openings, and a window in the corresponding door of each pair only whereby to provide a door intermediate of each of said window doors, said intermediate door serving to obstruct vision between the respective windows.

13. A starting device for animal races and the like comprising a box separated into a plurality of compartments, a pair of swinging doors for closing one end of each of said compartments, one of each pair of said doors being opaque, and the other of each pair of doors having a transparent section, each opaque door being interposed between doors having the said transparent section and being interposed in the line of sight between said transparent sections.

THOMAS A. KEEN.
